UNITED STATES PATENT OFFICE

160,540

COMBINED ELECTRICAL SOCKET AND CLAMP

Nicholas Riesinger, Scotch Plains, N. J.

Application March 2, 1950, Serial No. 8,290

Term of patent 3½ years

(Cl. D26—1)

To all whom it may concern:

Be it known that I, Nicholas Riesinger, a citizen of the United States, residing in Scotch Plains, county of Union and State of New Jersey, have invented a new, original, and ornamental Design for a Combined Electrical Socket and Clamp, of which the following is a specification, reference being had to the accompanying drawing, forming part hereof.

In the drawing:

Figure 1 is a side view of a combined electrical socket and clamp, showing my new design;

Figure 2 is a bottom view thereof;

Figure 3 is an end view.

I claim:

The ornamental design for a combined electrical socket and clamp, as shown.

NICHOLAS RIESINGER.
